UNITED STATES PATENT OFFICE.

RUDOLF WAGNER, OF HAMBURG, GERMANY, ASSIGNOR TO STAR CONTRAPROPPELLER LTD. A./S., OF CHRISTIANIA, NORWAY.

SCREW PROPELLER.

Application filed June 15, 1921. Serial No. 477,738.

(GRANTED UNDER THE PROVISIONS OF THE ACT OF MARCH 3, 1921, 41 STAT. L., 1313.)

To all whom it may concern:

Be it known that I, RUDOLF WAGNER, chief engineer, a citizen of the German Republic, residing at Hamburg, Germany, have invented certain new and useful Improvements in Screw Propellers, of which the following is a specification.

My invention comprises improvements in and connected with screw propellers and particularly combination of screw propellers with fixed counter propellers. The latter which have been fixed in the rear of the revolving propeller, serve for the direction of the revolving propeller stream into an axial flow. In known constructions, the vertical portion of the rudder post, upon which the rudder is mounted, has never been made use of to assist in the production of this directive effect, but it has been disposed between two laterally situated blades of the counter propeller and exposed to the propeller stream. Not only was this post not utilized, but, in addition, it offered a not inconsiderable resistance to the propeller stream, seeing that there was a somewhat intensive impact of the said stream against the post. This defect was partly avoided by disposing vertical blades of the counter propeller in front of the side of the post concerned, but the post still stood out or projected beyond the blades in question and offered resistance.

According to my invention, the aforesaid defects are avoided by shaping the forward edge portion of the rudder post somewhat in the form of a blade of sufficient width for imparting axial direction to the stream coming from the propeller. The portion so shaped is preferably that portion lying within the circle formed by the tips of the revolving blades as seen from the stern. In this manner an integral combination of the counter propeller with the rudder post is obtained, and the blade shaped portion of the said post may also serve for the attachment of laterally situated blades of a counter propeller. In this way, the previously proposed extension of two of the auxiliary or counter blades beyond the circle described by the tips of the revolving propeller and outwards to the hull of the ship, for the purpose of securing the counter propeller, is avoided, such extension of the blades was disadvantageous, because parts of these ex-

tensions were submerged so that they offered resistance. It is not necessary for the blade-shaped portion of the rudder post to be made in one piece with the rudder post itself, as it may be separable from the rudder post proper and so as to make a joint, either transversal or longitudinal, for enabling, for example, the main propeller to be readily removed.

In order to enable the invention to be readily understood reference is made to the accompanying drawings, in which:

Figure 1 is a side elevation of the stern part of a ship fitted with a counter propeller and rudder post in accordance with these improvements.

Figure 2 is an end elevation of the construction seen in Figure 1.

Figure 3 is a cross section on the line A—B of Figure 1.

Figure 4 is a cross section on the line C—D of Figure 1.

Figure 5 is a rear elevation of a modified construction differing somewhat from that seen in Figure 2.

Figure 6 is a front elevation of the counter propeller and lower portion of the rudder post seen in Figure 5.

Figure 7 is a cross section of another modified construction of blade formation on the rudder post and of a rudder mounted thereon.

Figure 8 is a view similar to Figure 1 of another construction adapted for facilitating the removal of the main propeller.

Figure 9 is a cross section on the line E—F of Figure 8.

Figure 10 is a cross section on the line G—H of Figure 8.

Figure 11 is a plan section showing another mode of removably mounting the blade like portions on the rudder post proper, and

Figure 12 illustrates a method of mounting a hollow blade-like portion on the rudder post proper.

Referring to Figure 1, 1 is the stern post, 2 is the rudder post, 3 is the counter propeller, 4 is the main propeller, and 5 is the rudder of a single screw propeller ship. In this construction, the rudder post 2 is assumed to be made in one integral piece with the portion 3 which is shaped in the fashion

2
of two blades of a rigidly fixed counter propeller. The distance 6 between the main and counter propellers is of sufficient width to prevent fouling by foreign bodies getting between. If the propeller is not of the type comprising a hub with removably mounted blades, the removal of the propeller may be accomplished by withdrawing the propeller shaft a little into the ship, thereby giving sufficient space for the withdrawal of the propeller from its shaft. Or the space 6 can be made so wide, and the propeller hub made as short as possible, that after the removal of the fixing nut it is possible to remove the main propeller from the space between the extremity of its shaft and the counter propeller. The central space between the counter propeller and the main propeller may be enclosed by a hood or cap 7 which also encloses the fixing nut, whereby resistance is reduced to a minimum. Also, the presence of the hood or cap prevents the winding around the nut of rope, or other material that may get between the propellers.

As will be seen clearly from Figures 1, 2 and 4 further blades 8 which may be used on the counter propeller may be removably attached to the rudder post portion 3, this removable attachment of the further blades giving a more favourable shape for the forging or casting of the rudder post than would be the case were the blades to be made integrally with the said post. The blades 8 may be formed in pairs and each pair may be secured to the centre part 3 by means of bolts 9, or may be riveted thereto. The radial length of the counter propeller blades 3 and 8 has been assumed, in this construction, to be considerably less than that of the main propeller because the reliability of the counter propeller is thereby increased and, as has been shown by theoretical investigation and practical experience, the outer portions of these blades have a quite inconsiderable useful effect.

As shown in Figures 1 and 3, it may be advantageous to shape these portions of the post 2 which lie outside of the propeller circle so that they are reduced forwardly to a cutting edge or are of somewhat streamline cross section, thereby reducing the resistance offered by these parts.

In Figure 4, the direction of rotation of the propeller 4 is indicated by the arrow 10 and the axially directed motion imparted by the blades of the counter propeller, and particularly of the blade-like portions 3 on the rudder post 2 is indicated by the arrow 11.

In the modification seen in Figures 5 and 6 it is again assumed that the blade-like portions 3 are formed integrally with the post 2, but, in order to simplify the construction there are only two laterally disposed blades 12, so that the counter propeller comprises

only four blades instead of six as in Figures 1 to 4. In this construction, however, the blades 12 are assumed to be formed integrally with the blades 3 and the post 2. To compensate for the reduced number of blades the latter may be made a little wider than in Figures 1 to 4, and, if necessary, the blades may be made with an increased twist or curvature at their outer ends. An advantage of this construction is the reduced cost for its manufacture, and a further advantage, which will be apparent from Figure 6, is the reduced diameter of hub 13 which is possible with this construction. Investigation has shown that it is important to make the fullest possible use of the core portion of the propeller stream, and this is rendered possible by the use of a hub of small diameter.

Figure 7 illustrates a construction in which another source of loss is avoided. Heretofore, in most cases, there was a relatively large space between the rear edge of the rudder post and the leading edge of the rudder, and in this space the propeller stream, having great intensity, suffered considerable loss by reason of the impact and eddies. According to Figure 7, the rudder post is constructed thicker than usual, which is possible when making it of the blade-like construction aforesaid, and this enables the pivot eyes 14 to be disposed that they do not protrude, being overlapped at the sides to a certain extent by recessed edge portions of the rudder and rudder post, and the forward edge of the rudder to be brought up close to the rear edge of the rudder post, so that the stream has a smooth passage past the joint between the rudder post and the rudder. The rudder is seen in its central position and the limits of its deviation to either side of the central position are indicated by the chain lines 15. When the rudder post is of large size it may be made hollow, as shown, for the purpose of reducing its weight.

Referring to Figures 8 to 10, the blade like part 3 is removably attached to the rudder post 2, principally for the purpose of enabling the main propeller to be readily removed from its shaft. As will be understood from Figures 8 and 10, the removal of the blade like part 3 gives a space extending from the end of the propeller shaft to the line 16 for the removal of the propeller 4, the line 16 being the transverse joint between the part 3 and the rudder post 2. The detachable part 3, fitted with auxiliary blades 8, may, if required, extend over the full height of the propeller cavity and, for the more reliable absorption of the lateral forces or for preventing the turning of the part 3 about the rudder post 2, it may extend over the propeller 4 by means of the curved arm or part 17. The part 17 may be

flanged, as seen in Figure 9, and the blade like part 3 may be secured in position partly by means of bolts 18 passed through the flange and the rudder post 2 or the stern 5 post, as the case may be, and partly by means of clamps 19 embracing the rudder post 2, bolts 20 being passed through the part 3 and the jaws of the clamps and set screws or clamping screws 21 or the like serving for 10 fastening the clamps to the rudder post 2. If desired, a foot portion 22 may be bolted to the keel bar 23 of the stern post. In this construction, the removable blade-like part 3 serves also for the stiffening of the rudder 15 post 2. As will be seen from Figure 10, the rear edge of the part 3 is of the same thickness as the forward edge of the post 2 against which it abuts, so that a favourable surface for the guidance of the propeller stream is 20 afforded.

According to Figure 11 the blade like portion 3 of the rudder post is divided into two parts 3 and 3' in a central perpendicular plane 24 by the hub of the counter propeller 25 and the rear edge portions of these blades 3 and 3' bear against or lap over respective sides of the rudder post 2 in planes parallel 30 with the longitudinal axis of the ship. The rear edge portions have sufficient thickness for providing, for example, a flange for over-lapping the post 2 at the back side of the blades, whereby the front sides may merge into the appropriate surfaces of the post 2, as seen in Figure 11 so that the 35 stream has a smooth passage past these surfaces and no resistance is created. The removable blade parts 3 and 3' may be attached to the post 2 by means of bolts 26.

According to Figure 12, the blade-like

portions are made hollow and, conveniently, 40 of sheet metal 27. At their rear edge portions, these blades embrace the post 2, as shown, being attached thereto by bolts 28, or by screws or rivets. If the blades are made each of two plates, the forward edges 45 of such plates may be united by screws, bolts or rivets, or, if desired, by welding. The blades may, however, be made by folding and bending a single sheet of metal, as will be readily understood. 50

What I claim is:—

1. An improved propelling means for ships comprising, in combination, a screw propeller, and a rudder post, forward portions of the vertical body of said post being 55 blade shaped whereby to act as guiding apparatus.
2. A propelling means according to claim 1, said rudder post carrying laterally disposed guide blades. 60
3. A propelling means according to claim 1, said blade shaped portions being jointed to the post.
4. A propelling means according to claim 2, said blade shaped portions being jointed 65 to the post.
5. A propelling means according to claim 3, and clamp means for connecting the blade shaped portions and the post.
6. A propelling means according to claim 4, and clamp means for connecting the blade shaped portions and the post. 70

In testimony whereof I affix my signature in presence of two witnesses.

RUDOLF WAGNER.
